[57] **ABSTRACT**

A back-side light-emitting diode comprised of an N-type free-standing monocrystalline planar substrate of a III-V ternary compound in which a P-type impurity is diffused into one of the planar surfaces, of the substrate, with the distance x in microns from the junction depth to the other planar surface conforming to the relationship $x = 0.5/\alpha$, where α is the absorption coefficient of said compound at a 7,000 Angstrom wavelength.
